[57] **CLAIM**

The ornamental design for a rolling fence gate supporting mechanism, as shown and described.

DESCRIPTION

FIG. 1 is a top, front, right end perspective view of the supporting mechanism for a rolling fence;

FIG. 2 is a top, back, left end perspective view thereof;

and

FIG. 3 is a bottom elevational view thereof.

The broken lines showing the gate and fence are for illustrative purposes only and form no part of the claimed design.

FIG. 1.

FIG. 2.
